UNITED STATES PATENT OFFICE.

HENRY MESINGER, OF NEW YORK, N. Y.

SADDLE.

Application filed September 6, 1924. Serial No. 736,200.

To all whom it may concern:

Be it known that I, HENRY MESINGER, a citizen of the United States, and a resident of the city, county, and State of New York, 5 have invented certain new and useful Improvements in Saddles, of which the following is a specification.

This invention relates to saddles and more particularly to a saddle for motor-cycles, 10 bicycles and similar vehicles, and has for its primary object to provide a rear end cushioning system for such saddles of simple and durable construction and high operating efficiency.

15 It is another object of the invention to provide an improved mounting and arrangement of the compression and tensioning springs of the cushioning system between the rear end of the saddle top and the supporting frame therefor, whereby shock, jar or vibration will be most effectively absorbed and the ease, comfort and sense of security of the rider appreciably increased.

20 With the above and other objects in view, the invention consists in the improved saddle, and in the form, construction and relative arrangement of its several parts as will be hereinafter more fully described, illustrated in the accompanying drawings and 25 subsequently incorporated in the subjoined claims.

In the drawings wherein I have shown several simple and practical embodiments 30 of the invention and in which similar reference characters designate corresponding parts throughout the several views—

Figure 1 is a side elevation partly in section, illustrating one embodiment of the present improvements;

40 Figure 2 is a rear end elevation partly in section; and

Figure 3 is a view similar to Figure 2, showing a slightly modified form of the device.

45 In the construction illustrated in the accompanying drawings, the saddle top 5 may be of any conventional form and construction and is suitably secured upon a bottom or base plate 6 which constitutes a cantle for

50 the saddle. This saddle top or seat is supported by a frame consisting of longitudinally extending spaced bars 7 which are connected to each other intermediate of their ends by a post clamping device 8, which 55 constitutes no part of my present improve-

ments and may be of any preferred type. The forward ends of these bars 7 which are relatively close to each other, have secured between them one end of the front spring 9, the other end of which extends beneath the 60 forward end of the cantle plate 6 and is rigidly fixed thereto by a suitable bolt indicated at 10.

Rearwardly of the post clamping device 8, the bars 7 are offset and more widely 65 spaced apart, as clearly shown in Figure 2 of the drawings, the rear extremities of said bars being connected with each other by a suitable yoke member 11, said bars and the ends of the yoke member having coinciding 70 openings to receive the connecting bolts 12 which have the clamping nuts 13 threaded upon their inner ends.

In suitable spaced clips 14, fixed to the underside of the cantle plate 6 adjacent the 75 rear end thereof, the intermediate portion of an inverted U-shaped rod 15 is pivotally engaged. The spaced vertical arms 16 of this rod extend downwardly at the outer sides of the rear ends of the respective frame 80 bars 7. Upon the lower end of each depending arm 16 of the rod 15, a sleeve 17 is loosely engaged, said sleeve being retained upon said arm by the collar 18 and pin 19. However, if desired, nuts or any suitable 85 means may be substituted for these collars to prevent the downward movement of the sleeve with respect to the arm 16.

The lower end of each sleeve 17 has its 90 wall reduced in thickness and formed, with a cup-shaped annular flange 20 which receives an eye 21 formed on the lower end of the tension spring 22 which surrounds said sleeve. This spring and the sleeve 17 are approximately the same length, and the 95 upper end coil of said spring is also provided with an eye 23 which is engaged upon the bolt 12 between the head thereof and the outer side of one of the frame arms 7 and is securely clamped against said arm by the 100 nut 13. Preferably, a washer plate 24 is interposed between the upper side of the eye 21 and an annular shoulder 25 on the lower end of the sleeve 17.

The upper end of the sleeve 17 is also reduced to provide a shoulder 26 thereon upon which the washer plate 27 is engaged. This washer provides a seat for the lower end coil of a compression spring 28 which extends around the vertical arm 16 of the rod 105 110

15 between said sleeve and the transverse portion 15 of said rod. The upper end coil of this compression spring is vertically extended as at 29 and engaged against the 5 underside of the cantle plate 6 of the saddle seat, as clearly shown in Figure 1 of the drawings, thus insuring a straight vertically applied pressure upon the upper end coil of the compression spring which will be transmitted through the other spring coils to the 10 sleeve 17. Accordingly, said spring will exert little or no lateral pressure upon the upper end of said sleeve which would tend to cause a pivotal or swinging movement of the rods 15 in the clips 14.

15 In Figure 3 of the drawings, I have illustrated a slightly different form of the device wherein the compression spring 28' is of greater length and extends through the tension spring 22, the lower end coil of said compression spring being seated upon the eye 21 which is connected to the lower end of said sleeve. Otherwise the construction 20 of this alternative embodiment of the device 25 is the same as that previously described.

30 In either form of the invention herein referred to, it will be evident that the vertical movement of the rear end of the saddle seat is effectively cushioned by the compression and tension springs.

35 In the operation of the device, it will be seen that in the first downward movement of the rear end of the saddle seat, the vertical arms 16 of the rod 15 move through the sleeves 17 which are supported by the tension springs 22, thereby compressing the springs 28 or 28', as the case may be. After these springs have been compressed, they transmit pressure through the sleeves 17 to the 40 lower ends of the tension springs 22 and thus expand said springs so that the continued or further downward movement of the rear end of the saddle seat is resisted by said tension springs. Since as above explained, the compression springs exert a direct downward vertical force upon the sleeves 17, the compression springs 22 will 45 promptly respond when the saddle seat is subjected to a very heavy weight or pressure, as is occasioned for instance upon the wheels of the cycle passing over ruts, rocks or other major obstructions in the roadway. Thus it will be appreciated that my new saddle cushioning means will very effectively 50 absorb shocks or jars which would otherwise be transmitted through the cycle to the saddle seat to the great discomfort of the rider. At the same time, it will be seen that my present improvements provide a cushioning system for such saddles which is quite simple in its construction, rugged and durable, and capable of production at 55 nominal cost.

60 While I have herein illustrated and described several practical examples of my

present improvements, it will nevertheless be understood that the device is susceptible of embodiment in many other alternative forms, and I therefore reserve the privilege of resorting to all such legitimate changes 70 in the form, construction and relative arrangement of the several detail parts thereof as may be fairly embodied within the spirit and scope of the invention as claimed.

75 I claim:

1. A saddle including a saddle top, a supporting frame therefor connected at its forward end to the saddle top, arms depending from the rear end of the saddle top, tension springs surrounding the respective arms and connected at their upper ends to said frame, said arms moving through said springs without expanding the same in the initial downward movement of the rear end of the saddle seat, and compression springs surrounding said arms and compressed in such initial movement of the seat end and thereafter transmitting a direct vertical thrust to the lower end coils of the tension springs in the further downward movement 80 of the seat end to expand the latter.

2. In a saddle, a saddle top, a longitudinal supporting frame connected at its forward end to said saddle top, arms depending from the saddle top at the outer side of said frame, a sleeve loosely engaged upon the lower end of each of said arms, tension springs having their lower end coils connected to the respective sleeves and having their upper end coils connected to said frame, compression springs surrounding said arms and resisting the initial downward movement of the rear end of the said seat, said arms moving through said sleeves without expanding the tension springs in such initial movement of the seat, the lower ends of said compression springs being engaged with said sleeves to apply a direct vertical pressure upon the lower coils of the tension springs in the continued downward movement of the seat end to expand the latter springs.

3. In a saddle, a saddle top, a longitudinal supporting frame connected at its forward end to said saddle top, arms depending from the saddle top at the outer side of said frame, a sleeve loosely engaged upon the lower end of each of said arms, tension springs having their lower end coils connected to the respective sleeves and having their upper end coils connected to said frame, compression springs surrounding said arms and resisting the initial downward movement of the rear end of the said seat, said arms moving through said sleeves without expanding the tension springs in such initial movement of the seat, the lower end coils of said compression springs having bearing engagement upon the upper ends 120 of said sleeves to urge the sleeves down-

wardly upon said arms in the continued downward direction of the seat end and thereby expand said tension springs.

4. A saddle including a saddle top, a supporting frame therefor connected at its forward end with the saddle top, spaced arms depending from the rear end of the saddle top, tension springs surrounding said arms and fixed at their upper ends to said frame, and means for expanding said tension springs in the downward movement of the rear end of the saddle by the transmission of a direct vertical thrust to the lower end coils of said springs, said means comprising compression springs surrounding the respective arms and having bearing contact at their upper ends against the underside of the saddle seat.

5. A saddle including a saddle seat, a supporting frame therefor connected at its forward end to said seat, a U-shaped rod piv-

otally mounted upon the underside of the saddle seat at its rear end and having spaced arms depending at opposite sides of said frame, a tension spring surrounding the lower end of each arm connected at its upper end to the frame, and means for resisting the initial downward movement of the rear end of the saddle seat, comprising compression springs surrounding said depending arms and arranged to impart a thrust in a direct vertical line upon the lower end of said tension springs to expand the latter in the continued downward movement of the seat end, the upper end coils of said compression springs being vertically extended and engaged against the underside of the saddle seat.

In testimony that I claim the foregoing as my invention I have signed my name hereto.

HENRY MESINGER.
